UNITED STATES PATENT OFFICE

161,332

STOCKING

Herbert N. Goodman, New York, N. Y., assignor to Triumph Hosiery Mills, Inc., New York, N. Y., a corporation of New York

Application March 10, 1950, Serial No. 8,450

Term of patent 14 years

(Cl. D47—7)

To all whom it may concern:

Be it known that I, Herbert N. Goodman, a citizen of the United States of America, residing at the city, county, and State of New York, have invented a new, original, and ornamental Design for a Stocking, of which the following is a specification, reference being had to the accompanying drawing, forming part thereof.

In the drawing:

The figure is a side view of a stocking, showing my new design.

I claim:

The ornamental design for a stocking, substantially as shown.

HERBERT N. GOODMAN.
